UNITED STATES PATENT OFFICE.

JOHN VAN EPS, OF SOMERVILLE, NEW JERSEY.

MUSIC-LEAF TURNER.

SPECIFICATION forming part of Letters Patent No. 349,540, dated September 21, 1886.

Application filed April 20, 1886. Serial No. 199,480. (No model.)

To all whom it may concern:

Be it known that I, JOHN VAN EPS, a citizen of the United States, residing at Somerville, in the county of Somerset and State of New Jersey, have invented certain new and useful Improvements in Music-Leaf Turners; and I do hereby declare that the following is a full, clear, and exact description of the same, reference being had to the annexed drawings, making a part of this specification, and to the letters and figures of reference marked thereon.

Figure 1 of the drawings is a perspective view of my improved music-leaf turner, showing it applied to what is known as the "umbrella music-stand," used in bands or orchestras; Fig. 2, a similar view of my invention, showing it adapted for use on a piano or organ; Fig. 3, a detail perspective view of the supporting-bracket and its attachments; and Fig. 4, a detail under plan view of the supporting-bracket and spring-latch device connected thereto, and a portion of the key-plate for operating the latch, shown in dotted lines.

The present invention has for its object to provide a simple and effective device for turning the leaves of sheet or other music bound in book form, and a device that will be durable, not easily got out of order, can be manufactured at a comparatively small cost, and a device that will be positive and certain in its action, which objects I attain by the construction substantially as shown in the drawings, and hereinafter described and claimed.

In the accompanying drawings I have shown in Fig. 1 what is termed an "umbrella music-stand," consisting of the music-support A, adjustably connected to the upper end of a rod, a, which is extensible within a tubular standard, B, and held in its adjusted position by set-screw b. This standard B is provided with hinged or pivoted tripod-legs c, held extended by detachable braces d, pivotally attached to the legs and engaging with the lower end of the standard.

The above is one of many forms of music-stands to which my invention is applicable, and is shown simply to illustrate the application and use of the mechanism for turning the leaves of the music, which is connected to an adjustable and removable bracket, C, upon the

music-support. To this bracket is pivotally attached a series of arms, D, provided at their outer ends with upright leaf-holding devices E, consisting each of two wires, between which the leaf is placed and held. Any desirable number of these arms D, with the leaf-holding devices E, may be employed, and previous to turning the music-leaves and before commencing a piece of music the leaves are all held upon one and the same side of the music-leaf support A, as shown in Fig. 1. This is attained by a spring-latch device, F, pivotally attached to the end of the bracket C, which holds together the arms D and devices E, between which the leaves are inserted. When it is desired to turn over one of the music-leaves, the latch F is depressed, which releases the upper one of the series of arms D, and immediately thereafter a suitable spring, e, (one being employed for each of the arms,) will automatically carry the arm to the opposite side of the support A, and with it the leaf of music. This latch F consists of a flat metal plate recessed to form a keeper, l, for retaining the arms D together preparatory to turning the leaves, and is also formed with a cam, m, so that when bringing the arms back to their normal position they will be raised as the arms come in contact with the inclined face of the cam, and thus automatically engage with the keeper as the arms pass beyond the cam, this construction of the latch being considered of great importance to the successful operation of the device.

As a means for operating the latch F, I have shown in Fig. 1 a cord, f, extending down to one of the tripod-legs c, and connecting with a foot-pedal, g; but any other desirable and convenient means may be employed for operating the latch by the foot or by the hand, the latter being effected by the use of a key-plate, G, which may be detachably connected to the latch in any desirable manner. After the latch F has been depressed it resumes its normal position by means of the spring h, to hold the remaining ones of the arms D together, and for this reason I term the latch a "spring-latch device."

I do not desire to confine myself to any particular means of pivotally connecting the arms

D to the bracket C; but in the present instance I prefer providing the end of each arm with a collar or sleeve, *i*, to fit over a post upon the bracket.

5 It is evident that many changes or modifications in the details of construction as would come within ordinary mechanical skill may be made without departing from the principle of my invention, and I therefore reserve this right
10 and the right to apply the device for turning music or other leaves, and to whatever uses it may be found applicable.

In Fig. 2 I have shown my invention adapted for attachment to a piano or organ, the
15 music-support being shown at I, and provided with hangers K, to catch on a piano or organ, the bracket C being attached to the support in any suitable manner. Near the center of the support I are connected two upright parallel rods, L, to place sheet-music between, to keep the leaf-turners from throwing it off the support. The support I is provided
20 with feet *k*, to take the weight of the attachment off the hangers K, and make it more steady when operated.

25 The hangers K and rods L may be detachably connected to the support I, or adapted to close down thereon when not in use, to make the device compact.

Having now described my invention, what I claim as new, and desire to secure by Letters Patent, is—

1. In a leaf-turner, a removable and adjustable bracket provided with a series of arms carrying holding devices for the leaves, and springs for automatically operating the arms, in combination with a spring-latch device pivoted to the bracket and consisting of a metal plate recessed to form a keeper to hold the arms together upon the side of the bracket, and having a cam to raise and guide the arms to the keeper, and suitable means for operating or depressing the latch, substantially as and for the purpose set forth.

2. In a leaf-turner, a suitable support provided with legs, in combination with hangers and two parallel upright rods, between which the sheet-music is held, as specified.

In testimony that I claim the above I have hereunto subscribed my name in the presence of two witnesses.

JOHN VAN EPS.
